UNITED STATES PATENT OFFICE

102,697

DESIGN FOR A CLOCK

Ossian K. Mitchell, Chicago, Ill.

Application December 5, 1936, Serial No. 66,336

Term of patent 14 years

To all whom it may concern:

Be it known that I, Ossian K. Mitchell, a citizen of the United States, residing at Chicago, in the county of Cook and State of Illinois, have invented a new, original, and ornamental Design for a Clock, of which the following is a specification, reference being had to the accompanying drawing, forming a part thereof.

Fig. 1 is a side elevation; and

Fig. 2 is a top plan view of a clock showing my new design.

The characteristic features of my design reside in the geographical globe with a dial or time telling band revolving around it and in the marking of time zones on said globe so that the time can be noted thereon in various parts of the world, simultaneously.

I claim:

The ornamental design for a clock, substantially as shown and described.

OSSIAN K. MITCHELL,
